TRANSFORMER

Ernest H. Freeman, Chicago, Ill., assignor to
 Hirsch Epstein and Louis R. Duman, Chi-
 cago, Ill.

Application May 13, 1946, Serial No. 669,228

6 Claims. (Cl. 315—257)

1

This invention relates to electric transformers and reactors for glow discharge tubes, particularly hot cathode tubes such as the fluorescent tube lighting lamps.

Transformers of the type of the present invention are designed generally to operate two lamps in a circuit including a condenser in series with one of the lamps to produce a phase difference of the currents of the tube lamps, thereby reducing the flicker and also improving the power factor of the combination.

It is one of the objects of the present invention to provide a simple, compact, sturdy, reliable and inexpensive transformer having the necessary leakage reactance so that the action of either one of the lamps will not adversely affect the other to any substantial extent.

In a transformer of the above mentioned character it is desirable that the windings that supply current to the respective lamps shall be in such relationships to one another and to the primary winding that the action of each lamp will produce a minimum effect on the action of the other. Transformers of this type are generally arranged with separate secondaries for the leading and the lagging lamps, respectively, which secondaries are connected in auto transformer relationship with the primary.

It is desirable to have an exceedingly low leakage flux between the primary winding and that secondary which supplies current to the leading lamp. Heretofore it has been proposed to accomplish this result by making the transformer core structure in the form of an elongated, hollow rectangular core on which the primary is divided into two separate coils placed one on one longitudinal leg of the core and the other on the other longitudinal leg of the core and, in such an arrangement, it has heretofore been further proposed to divide the secondary which supplies current to the leading lamp into two separate series connected coils one on each of the two longitudinal legs of the transformer core and adjacent the primary. In order to reduce the leakage reactance flux it has been proposed to make the two secondary coils above referred to concentric with the two primary coils. This has been found to be satisfactory. The cost of a primary coil with the secondary coil concentric therewith, as used in such arrangements where in there are two series connected primary coils and two series connected secondary coils has been, in the main, only a small amount less than the combined costs of separate primary and secondary coils. This is due to the fact that in

2

the transformer structures of the past which were provided with a concentric secondary and primary it was necessary to provide two separate insulated leads from the primary winding and two separate insulated leads from the secondary winding, the primary leads being in the main insulated from the secondary leads because two separate primary windings on the different legs of the core had to be connected in series and two separate secondaries on the different legs of the core had to be connected in series.

It is one of the objects of the present invention to reduce the cost of the concentric coils on a glow discharge tube transformer by providing an arrangement wherein a single primary coil is used which has concentric therewith a single secondary coil for supplying the current to the leading lamp. These coils are connected in auto transformer relationship. In view of the fact that it is not necessary to connect two separate primaries in series and two separate secondaries in series I have found that the two coils that constitute the respective primary and the secondary for the leading lamp can be wound as a single coil with end taps and one intermediate tap. For instance, if the primary coil is to have, say, 1500 turns and the secondary concentric therewith is to have 1000 turns, then the coil is originally wound with 2500 turns and, during the winding of the coil, a tap is provided at a point 1500 turns from one end of the coil. This tap together with the end of the coil which is 1500 turns away therefrom constitute the primary leads. The two ends of the coil that are 2500 turns apart constitute the load supply leads with the result that the last 1000 turns on the 2500 turn coil is connected in step-up auto transformer relationship with the first 1500 turns on the coil. This arrangement is, of course, possible only in a transformer core where the primary winding is in the form of a single coil as distinguished from one in which the primary winding is in the form of two separate series connected coils.

45 The coil consisting of a primary with its concentric secondary, and another coil which constitutes the secondary for the lagging lamp, are both placed on a transformer core of the shell type, the iron laminations of which are assembled 50 in the usual manner.

The attainment of the above and further objects of the present invention will be apparent from the following specification taken in conjunction with the accompanying drawing forming a part thereof.

In the drawing:

Figure 1 is a view of a transformer of the present invention illustrated in circuit with two hot cathode glow discharge lamps;

Figure 2 is a diagrammatic view of the circuit of Figure 1; and

Figure 3 is a plan view of one of the core laminations.

Reference may now be had more particularly to the drawings wherein like reference numerals designate like parts throughout.

The transformer of the present invention is indicated in general by the reference numeral 1 and consists of an elongated rectangular core 2 built up of laminations 3. Each lamination 3 is formed of an elongated rectangular sheet of transformer iron which is stamped to form two slots 5 and 6 leaving a central core portion or finger 7 which extends through the transformer coils in a manner to be more fully set forth as this description proceeds. The lamination is stamped to provide very narrow slits 8 and 9. The finger 7 can therefore be flexed out of the plane of the rest of the sheet for insertion through the coils. The successive laminations are assembled from opposite sides of the coils so that the slits 8-9 of adjacent laminations are on opposite sides of the core. The opposite sides 10 and 11 of each lamination are of a combined width equal to or somewhat greater than the width of the central finger 7.

The transformer core has what appears to be two separate spaced apart coils 12 and 13 thereon with the fingers 7 of the assembled stack of laminations extending through the coils. The coil 12 is a single winding coil that supplies current to the lagging lamp. The coil 13 is a double winding coil consisting in effect of a single coil with end terminals, indicated at 14 and 15, and an intermediate tap 16. In one construction the coil 13 was provided with 2570 turns and the tap 16 was electrically connected to the coil at a point 1500 turns distant from the terminal 14. This divides the coil 13 into a primary winding 20 and a secondary winding 21 having in this instance 1500 and 1070 turns, respectively, both windings being closely coupled and each winding extending for the full length of the coil 13. The coil 12 in this instance had 1225 turns. In view of the fact that the coil 12 had approximately half the number of turns of the coil 13 it was made of approximately half the length thereof so that both coils were of approximately the same internal and external diameters, thus substantially filling the lateral space between the center finger 7 of the transformer laminations and the longitudinal end strips.

The leads 14 and 16 which constitute the terminals of the primary coil 20 are connected across a line 25, which may constitute a source of 120 volt 60 cycle commercial alternating current. The secondary coil 12 is connected in step-up auto transformer relationship with the primary coil 20, as may be seen from the circuit of Figure 2, and then connected to one of the filaments of a hot cathode fluorescent glow discharge lamp 27, which filament is connected to the opposite filament of the lamp through a usual starter switch 28, the opposite filament of the lamp being then connected to the line. The secondary 21 is connected at its lead 15 to a reactor 30 (Fig. 2) from which the circuit goes to a condenser 31, thence in series to the heating filament 32 of a hot cathode glow discharge fluorescent lamp 33, thence through a starting or com-

pensating winding 34 and a starter switch 35 to the opposite filament 36 of the lamp 33, from which the circuit is then connected back to the line. The lamp 27 takes the lagging current and the lamp 33 the leading current. The reactor coil 30 and the starting or compensating winding 34 are two concentric windings, as indicated at 40 in Figure 1, and are mounted on a laminated iron core structure 41 which is of the same construction as the core 2 of Figure 1.

The transformer 1 and the reactor and the condenser 31 are all enclosed in a single sheet iron container and the free space is filled with the usual type of tar-like insulating compound.

15. By providing the reactor 30 and the starting or compensating winding 34 it is possible to use a much smaller capacity condenser 31 than would otherwise be required. For instance, in one installation the reactor coil 30 had 520 turns and 20 the starting or compensating coil had 365 turns where the lamps 23 and 27 were of the 40-watt type and the transformer 1 was of a size such as previously set forth. The necessary condenser 31 was of only four microfarads capacity.

25. It is to be noted that after the starting switch 35 of the leading lamp 33 opens its circuit the starting or compensating winding 34 is disconnected and only the reactor 30 and condenser 31 are in circuit with the lamp.

30. In compliance with the requirements of the patent statutes I have here shown and described a preferred embodiment of my invention. It is, however, to be understood that the invention is not limited to the precise construction here shown, the same being merely illustrative of the principles of the invention. What I consider new and desire to secure by Letters Patent is:

40. 1. A transformer for two discharge tube loads, comprising a rectangular core having a central core section located between and parallel to the longitudinal sides of the core, a first coil on said central core section, said coil having terminals and an intermediate tap, the coil turns between one terminal and the intermediate tap constituting a primary winding and the coil turns between the intermediate tap and the other terminal constituting a secondary winding connected in step-up auto transformer relationship to the primary winding for energizing one discharge tube load, and a second coil on said central core section and spaced from the first coil longitudinally of the core and comprising a second secondary winding and less closely coupled to the primary than is said first mentioned secondary, said 45 second coil being also connected in step-up auto transformer relationship with said primary winding for energizing another discharge tube load, the connection between the second coil and the primary being at said intermediate tap.

60. 2. A transformer for two discharge tube loads, comprising a rectangular core having a central core section located between and parallel to the longitudinal sides of the core, a first coil on said central core section and extending therefrom substantially to the longitudinal sides of the core, said coil having terminals and an intermediate tap, the coil turns between one terminal and the intermediate tap constituting a primary winding and the coil turns between the intermediate tap and the other terminal constituting a secondary winding connected in step-up auto transformer relationship to the primary winding for energizing one discharge tube load, a second coil on said central core section and spaced from the first coil longitudinally of the core and comprising a

second secondary winding, said second coil being also connected in step-up auto transformer relationship with said primary winding for energizing another discharge tube load, the connection between the second coil and the primary being at said intermediate tap, and a condenser in series with the first one of the secondaries to cause it to take a leading current.

3. Apparatus for operating two discharge tube loads, comprising a transformer having a single primary winding, a secondary winding concentric with the primary winding, a second secondary spaced from the primary and less closely coupled thereto than is the first mentioned secondary, both secondaries being electrically connected to the primary at the same electrical point in step-up auto transformer relationship, a core for said windings, said core being of an elongated rectangular shape and having a central longitudinally extending core section between and parallel to the longitudinal sides of the core and extending centrally through said windings whereby the windings are embraced by the core, and leads from the respective secondaries for individual connection to different tube circuits.

4. Apparatus for operating two discharge tube loads, comprising a transformer having a single primary winding, a secondary winding concentric with the primary winding, a second secondary spaced from the primary and less closely coupled thereto than is the first mentioned secondary, both secondaries being electrically connected to the primary at the same electrical point in step-up auto transformer relationship, a core for said windings, said core being of an elongated rectangular shape and having a central longitudinally extending core section between and parallel to the longitudinal sides of the core and extending centrally through said windings whereby the windings are embraced by the core, leads from the respective secondaries for individual connection to different tube circuits, a condenser in the circuit of the lead from the first mentioned secondary, and a two coil reactor having an iron core separate from the aforementioned rectangular core, one of the reactor coils being connected in series circuit with the condenser and the other reactor coil having conductor leads therefrom for permitting the selective connection thereof into and out of said series circuit.

5. Apparatus for operating two discharge tube loads, comprising a transformer having a single primary winding, a secondary winding concentric with the primary winding, a second secondary spaced from the primary and less closely coupled thereto than is the first mentioned secondary, both secondaries being electrically connected to the primary at the same electrical point in step-up auto transformer relationship, a core for said

windings, said core being of an elongated rectangular shape and having a central longitudinally extending core section between and parallel to the longitudinal sides of the core and extending centrally through said windings whereby the windings are embraced by the core, leads from the respective secondaries for individual connection to different tube circuits, a condenser in the circuit of the lead from the first mentioned secondary, and a reactor in series with the condenser, said reactor having an iron core and being outside of the magnetic circuit of the transformer.

6. Apparatus for operating two discharge tube loads, comprising a transformer having a single primary winding, a secondary winding concentric with the primary winding and extending the full length thereof and closely coupled thereto, a second secondary spaced from the primary and less closely coupled thereto than is the first mentioned secondary, both secondaries being electrically connected to the primary at the same electrical point in step-up auto transformer relationship, a core for said windings, said core being of an elongated rectangular shape and having a central longitudinally extending core section between and parallel to the longitudinal sides of the core and extending centrally through said windings whereby the windings are embraced by the core, leads from the respective secondaries for individual connection to different tube circuits, a condenser in the circuit of the lead from the first mentioned secondary, a reactor in series with the condenser, said reactor having an iron core and being outside of the magnetic circuit of the transformer, an additional coil magnetically coupled to the reactor, and a discharge tube starter switch in the circuit of the tube connected in series with the condenser and circuit connections including said switch for connecting said additional coil in the starting circuit of said last mentioned tube and open circuiting said additional coil upon opening of the starting circuit of said last mentioned tube.
